LAMP SHADE

Albert A. Anger, Bedford Township, Monroe
County, Mich.

Application May 10, 1950, Serial No. 9,855

Term of patent 7 years

(Cl. D48—16)

To all whom it may concern:

Be it known that I, Albert A. Anger, a citizen of the United States of America, residing at Bedford Township, Monroe County, State of Michigan, have invented a new, original, and ornamental Design for a Lamp Shade, of which the following is a specification, reference being had to the accompanying drawing, forming part thereof.

In the drawings:

Fig. 1 is a side elevational view of a lamp shade, showing my new design;

Fig. 2 is a top plan view thereof; and

Fig. 3 is a fragmentary cross sectional view taken on the line III—III of Fig. 1.

The dotted lines shown in the drawing are for illustrative purposes only.

I claim:

The ornamental design for a lamp shade, substantially as shown and described.

ALBERT A. ANGER.
